UNITED STATES PATENT OFFICE.

GILBERT J. SINNOTT, OF BROOKLYN, NEW YORK, ASSIGNOR TO AMERICAN HIGH SPEED PRESS COMPANY, OF NEW YORK, N. Y., A CORPORATION OF NEW YORK.

CHASE.

1,262,857.

Specification of Letters Patent. Patented Apr. 16, 1918.

Application filed September 3, 1914. Serial No. 860,094.

To all whom it may concern:

Be it known that I, GILBERT J. SINNOTT, a citizen of the United States, residing at Brooklyn, in the county of Kings and State 5 of New York, have invented a new and useful Chase, of which the following is a specification.

This invention relates to a chase for use in printing on odd shaped articles, such for 10 example, as envelop blanks; and the principal objects thereof are to provide a simple and convenient construction by which the chase, after the type is locked up, can be adjusted angularly to accommodate articles 15 of different sizes, shapes, and angular positions without unlocking; and to provide automatic means for locking the chase in its adjusted positions without requiring any manipulation other than the mere adjust- 20 ment. The invention also involves improvements in details and features of construction as will appear hereinafter.

Reference is to be had to the accompanying drawings, in which—

25 Figure 1 is a plan of a chase and its holder constructed in accordance with this invention;

Fig. 2 is an end elevation of a portion of a press showing these parts mounted thereon 30 and appearing in section;

Fig. 3 is an enlarged plan of a portion of the chase holder;

Fig. 4 is an enlarged plan of the chase;

Fig. 5 is a sectional view on the line 5—5 35 of Fig. 3;

Fig. 6 is a sectional view on the line 6—6 of Fig. 3;

Fig. 7 is a sectional view on the line 7—7 40 of Fig. 4; and

Fig. 8 is a plan of a portion of the chase lock.

The invention is shown as applied to a machine of a kind in which the chase holder 10 is secured in position by means of an ad- 45 justable lever 11 and a spring-pressed lever 12. The chase holder is provided with the usual slanting surfaces for receiving the ends of these levers and is adapted to be secured in position by them so as to hold 50 the chase 13 which carries the type matter.

For the purpose of securing the above mentioned results the chase holder is pro- 55 vided with a central circular opening 14. This opening is bounded on the outer face

inner side two opposite segmental flanges 16 are provided separated from the flange 15 so as to provide grooves 17 opposite each other.

The chase 13 is provided with a pair of 60 segmental tongues 18 projecting from its circular surface and adapted to enter between the ends of the segmental flanges 16. In this way the chase can be inserted and removed by turning it to a certain position 65 and will be held in place when turned slightly away from that position. For the purpose of manipulating the chase it is provided with a pair of hand holes 19 on the opposite sides of the central space 20. This 70 space is of general rectangular shape and has four sides planed at right angles so that the type matter can always be locked up squarely.

On the circumference of the chase be- 75 tween the two tongues 18 are a series of teeth 21 cut into the edge of the chase. On the chase holder is a slideable lock 22 having teeth 23 on its end adapted to engage in the teeth 21 for the purpose of locking the 80 chase in position on the chase holder. This lock slides in a space 24 in the chase holder and in order that it may be guided properly it is provided with a spindle 25 working in a bored passage 26 in the body of the chase 85 holder. On this spindle is a collar 27 and beyond this a spring 28 which bears against a fixed surface of the chase holder. This serves to force the lock yieldingly against the teeth 21, so that when the chase is turned 90 for adjustment it will remain locked in its adjusted position automatically and without any attention on the part of the operator other than that required to turn the chase and get it into proper position. 95

The purpose of the adjustment to an angular position is indicated clearly by the dotted lines in Fig. 1 which show an envelop blank which is to be printed upon. It will be seen therefore that whatever the 100 shape of the blank to be printed upon or the position of the printing thereon this chase can be turned readily to accommodate it without unlocking the chase from the chase holder, without danger of loosening 105 the type or furniture, and without necessitating any special manipulation for the actual locking of the parts in adjusted positions.

Although I have illustrated and described 110

only a single embodiment of the invention, I am aware of the fact that many modifications can be made therein without departing from the scope of the invention as expressed in the claims. Therefore I do not wish to be limited in these respects, but what I do claim is:—

1. The combination with a chase holder, of a flat chase carried thereby flush therewith on its printing side and angularly movable thereon, and means for automatically locking the chase to the chase holder in all adjusted positions of the chase.
2. The combination with a chase holder having a circular opening therein, of a circular chase mounted in said opening in a position to cause the type carried thereby to project through said circular opening and adapted to be turned on its axis, said chase having teeth on its circumference, and a spring-pressed lock on the chase holder adapted to engage said teeth and hold the chase in its adjusted positions.
3. The combination of a chase holder having an opening therein provided with a pair of opposite flanges in the same plane on one side, and a chase adapted to fit in said opening and provided with a pair of tongues adapted to enter the free space between the ends of said flanges and pass behind said flanges when turned so as to be held in the holder.
4. The combination of a chase holder having a circular opening therein provided with a continuous circular flange on one side and a pair of opposite segmental flanges in

the same plane on the other side having a groove between said opposite flanges and the circular flange, and a circular chase adapted to fit in said opening and provided with a pair of segmental tongues adapted to enter the space between said segmental flanges and to pass into said groove when turned.

5. The combination of a chase holder having a circular opening therein provided with a continuous circular flange on one side and a pair of opposite segmental flanges on the other side having a groove between said opposite flanges and the circular flange, a circular chase adapted to fit in said opening and provided with a pair of segmental tongues adapted to enter the space between said segmental flanges and to pass into said groove, whereby said chase will be held in said opening, and means for locking the chase in its adjusted angular positions.

6. As an article of manufacture, a circular chase having an opening therein provided with four sides of a general rectangular shape and having two opposite projecting tongues along a portion of its circumference spaced apart circumferentially for supporting it.

In testimony whereof I have hereunto set my hand in the presence of two subscribing witnesses.

GILBERT J. SINNOTT.
